Primary Examiner — Kevin Rudzinski(74) *Attorney, Agent, or Firm* — Alan I. Cantor; Mark S. Bicks; Alfred N. Goodman(57) **CLAIM**

The ornamental design for a luminaire housing, as shown and described.

DESCRIPTION

FIG. 1 is a top perspective view of a luminaire housing in accordance with the present invention;

FIG. 2 is a bottom perspective view of the luminaire housing of FIG. 1;

FIG. 3 is a top plan view of the luminaire housing of FIG. 1; FIG. 4 is a left side elevational view of the luminaire housing of FIG. 1, the opposite side being the mirror image of that shown;

FIG. 5 is a bottom plan view of the luminaire housing of FIG. 1;

FIG. 6 is a rear elevational view of the luminaire housing of FIG. 1; and,

FIG. 7 is a front elevational view of the luminaire housing of FIG. 1.

The broken lines illustrate portions of the luminaire housing that form no part of the claimed design.
